COMBINATION ASHTRAY, AIR CIRCULATOR
AND FILTERHenry J. Talge, Kansas City, Mo., and Jack E. Briar,
Shawnee Mission, Kans., assignors to Songrand Corpora-
tion, Kansas City, Mo., a corporation of Missouri

Filed Apr. 29, 1964, Ser. No. 79,732

Term of patent 14 years

(Cl. D62—2)

Fig. 1.

Fig. 2.

Fig. 3.

Fig. 4.

FIG. 1 is a top plan view of a combination ashtray, air circulator and filter embodying our new design;

FIG. 2 is a side elevational view thereof;

FIG. 3 is an end view thereof; and

FIG. 4 is a fragmentary sectional view taken along line 4—4 of FIG. 2 in the direction of the arrows.

The side and end not shown have substantially the same appearance as the respective side and end shown.

The dominant features of our design reside in the portions shown in solid lines.

We claim:

The ornamental design for a combination ashtray, air circulator and filter, as shown and described.
